FIG. 5

Philip J. Sonner
BY
William C. Edwards Jr.
ATTORNEY.

UNITED STATES PATENT OFFICE.

PHILIP J. SONNER, OF MOLINE, KANSAS.

GAS BURNER.

Application filed July 27, 1925. Serial No. 46,348.

To all whom it may concern:

Be it known that I, PHILIP J. SONNER, a citizen of the United States, residing at Moline, in the county of Elk and State of Kansas, have invented certain new and useful Improvements in Gas Burners, of which the following is a specification referring to the accompanying drawings, which form a part thereof.

10 The invention relates to an improved gas burner mechanism especially adapted for use under heavy pressures as well as under light pressures. Pressures of 15 to 20 pounds are quite customary in industrial uses, such for instance as in refineries and the like; by simple changes in adjustment, my device is readily adapted for use in domestic establishments where pressures may approximate three to four ounces. I do not 15 limit my invention to any particular pressure standard however, the foregoing being merely for purposes of illustration.

The uses and purposes of the invention will be best understood from a description 20 of the drawings, in which Fig. 1 shows a multiple combination of individual unit burners for an industrial gas burner outfit. Fig. 2 is an enlarged side elevation of Fig. 1. Fig. 3 is an enlarged side view of a single burner element and allied parts. Fig. 4 is a 25 top view of Fig. 3. Fig. 5 is a sectional view of a burner mechanism as taken along the line V—V Fig. 4 looking in the direction of the arrows. Fig. 6 is a sectional view 30 taken along the line VI—VI Fig. 5 looking in the direction of the arrows.

Similar numerals of reference indicate 35 corresponding parts throughout all the figures of the drawings.

40 Referring to the drawings; from the gas main pipe 10 are shown a plurality of gas pipes 10', 10'', 10''', 10'''' connected thereto, each serving a plurality of individual gas burner elements supported thereon as later 45 explained. Upon a gas pipe 10' for instance is seen a bracket 11 which includes a sleeve portion 11* enveloping said pipe 10' and adjustably spaced and secured thereupon by means of the screw 12. Mounted upon the 50 bracket arms 11 above the pipe 10' is a square or rectangular box-like element 13 secured by screws 14 to said bracket members. This element 13 is open at the top; it is preferably cast of iron or other suitable material 55 so as to provide four complete side walls and a base member 15. Vertically cast and cen-

trally arranged within the box-like member 13 is a tube-like cylinder section 16 extending more above than below the base 15 as seen in Fig. 5. A port in the pipe 10' at 60 17 is arranged in the vertical axis of the tube 16 during the adjustable assemblage. The bracket 11* may be perforated at 17* if said bracket happens to cover a port 17. The space 18 between the base of the tube 16 and the port 17 allows for air to mix with the gas coming from the supply pipe. The four inner corners of the member 13 are rounded and form column supports 19 extending upwardly to a point 20 below the upper edge 70 21 of the member 13. A cover element includes four upwardly flaring side elements 22, 23, 24, 25 which are shown in Fig. 5 supported upon the upper portions 20 of the posts 19. At 26 is the depressed central portion of the cover element and from which depends a four sided inverted box like element 27 open at its base 28. The upper end of the tube 16 is spaced a desired distance below the central portion 26 of the cover 80 while the base 28 is spaced a required distance above the bottom 15 of the member 13. In Fig. 4 will be noted four slots or gap spacings cast along the edges of the cover element at 29, 30, 31 and 32. At 33 and 34 85 are seen lugs cast upon the element 13 while companion lugs 35 and 36 are cast on said element upon or adjacent to the other pair of lower corners thereof. In Figs. 1 and 2 the grooves 37 and 38 of the lugs 35 and 36 90 engage the lugs 33 and 34 of another burner element while screws 39 penetrating the lugs 35 and 36 engage threaded holes 40 in the connecting lugs 33 and 34 as will be readily understood. This anchors the series of box-like elements 13 a spaced distance 41 apart. Pipe spacers 42 are seen in Fig. 2 further 95 maintaining this fixed gap spacing while bolt means 43 sleeved through said spacers 42 engage the walls of the elements 13. Accordingly spacings 41 separate the various elements 13 from one another or so that air passages are provided for combustion purposes. Each burner is substantially a Bunsen burner operating with increased efficiency.

The gas from the port 17 and air from space 18 enter the tube 16 and rise to contact the base of the cover 26 thence flow downwardly within the space included between the walls 27 and tube 16 to the base 15 thence upwardly between the walls 27

and 13 to pass out the four slots 29, 30, 31 and 32 where the mixture is ignited. Asbestos packing, fireclay or similar materials may be carried within the depression 26.

Having fully described my invention what I now claim as new and desire to secure by Letters Patent is:

1. In gas burners, a box-like element including four side members and a bottom member but open at the top, a tubular element centrally and vertically arranged as a part of the bottom of said box-like element and extending above and below said bottom; post elements one for each corner of said box-like element; a cover element having a depressed central portion and upwardly and outwardly flaring edge portions supported by said post elements; gap spacings as gas orifices between the edges of the cover element and the top edge portions of the four sided element; an inverted box-like element integral with the base of said cover element arranged above the tubular portion of the first mentioned box-like element.
2. In gas burners; a gas main, a port therein; a bracket carried by the gas main, a box-like element including four side members and a bottom member supported by the bracket, a tubular element as a part of the bottom of said box-like element vertically positioned above said port, a portion of said

tubular element extending below the bottom of said box-like element while a larger portion extending within and above the box-like enclosure; a post in each inner corner of said box-like element; a cover element supported upon said posts as a closure for said box-like element; gap spacings between the side edge portions of said cover and the upper edge portions of said box-like element; an inverted four-sided element integral with the base of said cover element arranged above the tubular portion of the first mentioned box-like element.

3. In gas burners a series of unit devices spaced apart and rigidly secured to each other; each unit device including a four-sided box-like element open at the top having a tubular element centrally arranged through the bottom thereof; a bracket supporting each device; a gas main supporting each bracket; a port in the main directly beneath the tubular element; posts in the corners of each unit; a cover supported upon said posts; gap spacings along the side edges of said covers as gas orifices and a depending inverted four sided element integral with the base of each cover arranged above the tubular element.

In testimony whereof I hereunto affix my signature.

PHILIP J. SONNER.
